UNITED STATES PATENT OFFICE.

JAMES HARRY THOMPSON, OF TRENTON, NEW JERSEY.

TELEPHONE APPARATUS.

No. 896,173.

Specification of Letters Patent.

Patented Aug. 18, 1908.

Application filed December 30, 1907. Serial No. 408,682.

To all whom it may concern:

Be it known that I, JAMES HARRY THOMPSON, citizen of the United States, residing at Trenton, in the county of Mercer and State of New Jersey, have invented new and useful Improvements in Telephone Apparatus, of which the following is a specification.

My invention has to do with telephones; and it has for its object to provide at a point intermediate the bell-box and the desk set of a telephone apparatus, a device calculated to pay out the connecting wires incident to the movement of the desk set away from the bell-box so as to permit of the desk set being used at different points in an apartment, and also adapted to take up slack of the said wires as the desk set is moved toward the bell-box, this with a view of keeping the wire taut between the bell-box and the desk set and avoiding the damage liable to be occasioned when the wires hang loose over or around a desk and between tables and the like.

To the attainment of the foregoing object, the invention consists broadly in the provision of spring-actuated means for winding the wires designed to lead to the desk set, and the arrangement of the wires on the winding means and the arrangement of the wires intermediate the bell-box and the winding means, whereby undue twisting and consequent injury of the wires during the use of the desk set is precluded.

With the foregoing in mind the invention will be fully understood from the following description and claims when the same are read in connection with the drawings, accompanying and forming part of this specification, in which:

Figure 1 is an elevation illustrating the preferred arrangement of my novel device, relative to the bell-box of a telephone apparatus. Fig. 2 is a vertical section of the device. Fig. 3 is a horizontal section taken through the device in a plane above the working parts thereof. Fig. 4 is a detail side elevation of the drum comprised in the device and showing the removable segment at one side of said drum, and Fig. 5 is a perspective view showing said segment as removed.

Similar letters designate corresponding parts in all of the views of the drawings, referring to which:

A is the bell-box of a telephone apparatus, which may be of the conventional or any other suitable construction, and B is the casing of my novel device which is located at a

suitable distance from the bell-box and is preferably, though not necessarily, arranged in the same horizontal plane as the box, after the manner illustrated in Fig. 1. The front wall of the said casing B preferably comprises two separable sections *a* and a bushing *b* interposed between and held by the contiguous portions of the said sections *a* and made up of two semi-circular sections. The side wall of the casing nearest the bell-box A is preferably made up of a section *b'* separable from a fixed section *b²*, and a sectional bushing *c* arranged and held between the sections *b'* and *b²*. In the interior of the casing and in grooves *d* formed in the upper and lower walls thereof is a partition made up of sections *e* which are separable and a sectional bushing *f*. In this connection it will be noted that the sectional walls and bushings described permit of my novel device being attached to the wires intermediate the bell-box and a desk set without entailing disconnection of the said wires from either the bell-box or the desk set. The bushings described may be of any suitable material, it not being essential to make the same of insulating material inasmuch as the wires between a bell-box and a desk set are ordinarily covered with insulating material.

Located in that chamber of the casing B which is remote from the bell-box A is a fixed frame C of suitable construction which preferably comprises a casing *g* for the reception of a coiled spring D which is connected at one end to the casing and at its opposite end to a shaft E, and is arranged to be put under tension by rotation of the said shaft in one direction and to serve to expand and rotate the shaft in the opposite direction. On the said shaft E is fixed a spur gear F, and with the said spur gear is intermeshed a pinion G, fixed on a shaft H which, like the shaft E, is journaled in the frame C. The said shaft H, however, extends laterally from the frame C, as best shown in Fig. 2, and on its extended portion is fixed by a set screw *h* or other suitable means, a drum I which is preferably flanged as shown. The said drum I may be made of any material suitable to its purpose, and in the preferred embodiment of my invention it comprises a body *i* having a central bore *j* and a radial groove *k* which communicates at its inner end with the said bore *j*, and a removable segment *l* set in one side of the body *i*, as best shown in Fig. 4, and forming part of the walls of the bore *j* and the

radial groove *k*. The said removable segment *l* is detachably fixed in the body *i*, preferably by screws *m*, Fig. 4, and by virtue of the provision of the said removable segment, it will be seen that the drum *I*, like the bushings before described, is adapted to receive the wires intermediate the bell-box *A* and the desk set (not shown) without entailing disconnection of said wires from either the bell-box or the desk set.

From the bell-box *A* the wires which are lettered *M* are carried through the bushing *c*, the bushing *f*, and the bore *j* and radial passage *k* of the drum *I*, in the order named, and, after being carried around the drum, are passed through the bushing *b* and off to the desk set to which they are connected in the conventional or any other suitable manner. In adjusting my improvements, the wires intermediate the bell-box *A* and the drum *I* are twisted in the direction opposite to that in which the drum rotates to pay off the wires one-half as many times as the drum is required to rotate in said direction, so that as the drum rotates in paying off the wires, the said portions of the wires between the bell-box *A* and the drum *I* are untwisted when half of the wires are fed off the drum, and incident to the rotation of the drum to pay off the remainder of the wires thereon, the said portions of the wires between the bell-box and the drum are twisted in the same direction as the drum rotates. For instance if it is necessary for the drum to make six complete revolutions to pay out the wires from the casing *B*, the wires when placed between the bell-box *A* and the drum *I* are twisted three times in the direction opposite to that in which the drum rotates to pay off the wires. Then when the wires are entirely fed off the drum, the wires between the bell-box and the drum are twisted three times in the same direction as the drum rotates to pay off the wires. This assures a minimum twist of the wires and prolongs the usefulness of the wires and my novel device as a whole and consequently constitutes an important feature of my invention.

In the use of my improvements it will be understood that the desk set connected to the wires that extend through the bushing *b* may be carried to and conveniently used at various points in an apartment, and that when the desk set is carried away from the casing *B*, the spring *D* is put under tension with the result that when the desk set is carried toward the casing *B* the spring will operate to rotate the drum *I* and thereby take up the slack of the said wires or portions of wires. The working parts of my improvements will in fact keep the portions of the wires between the casing *B* and the desk set at all times taut, and in that way will avoid the annoyance of the wires hanging loose and the resulting liability of the wires being

damaged or operating to drag papers and other unfastened objects from desks and the like.

Notwithstanding the practical advantages which I have ascribed to my improvements, it will be appreciated that the said improvements are simple and inexpensive in construction and are adapted to be expeditiously and easily installed, and all of the working parts of the improvements are well adapted to withstand the usage to which devices of corresponding kind are ordinarily subjected.

The construction herein illustrated and described constitutes the best practical embodiment of my invention of which I am cognizant, but it is obvious that in the future practice of the invention such changes or modifications may be made as fairly fall within the scope of my invention as defined in the claims appended.

Having described my invention, what I claim and desire to secure by Letters-Patent, is:

1. The combination in a telephone apparatus, of a bell-box, wires connected with the bell-box and adapted to be connected with a desk set or the like, and a device having sections arranged to receive the wires between them and to guide said wires and also having a drum and a spring connected with the drum; the drum comprising a body and a portion detachably connected with the body and arranged to hold the wires to the body, and the spring being arranged to be put under tension by the drawing of the wires off the drum and also arranged when the pull on the wires is released to rotate the drum and thereby take up slack of the wires.

2. In an apparatus for the purpose described, the combination of wires, and a device having separable sections arranged to receive the wires between them and to guide said wires and also having a drum and a spring connected with the drum; the drum comprising a body and a portion detachably connected with the body and arranged to hold the wires to the body, and the spring being arranged to be put under tension by the drawing of the wires off the drum and also arranged when the pull on the wires is released to rotate the drum and thereby take up slack of the wires.

3. The combination in an apparatus for the purpose described, of a drum, a spring connected with the drum and arranged to be put under tension by rotation of the drum in one direction and to rotate the drum, when released, in the opposite direction, and wires leading from a fixed point of connection to the center of the drum and from thence to the periphery of the drum; the portions of the wires intermediate the fixed point of connection and the drum being twisted in the direction opposite to that in which the drum rotates to pay off the wires one-half as many

times as the drum is required to rotate in said direction, for the purpose set forth.

4. The combination in a telephone apparatus, of a fixed bell-box, a drum fixed relative to the bell-box, a spring arranged to be put under tension by rotation of the drum in one direction and to rotate the drum, when released, in the opposite direction, and wires leading from the bell-box to the center of the drum and from thence to the periphery of the drum; the portions of the wires intermediate the bell-box and the drum being twisted in the direction opposite to that in which the drum rotates to pay off the wires one-half as many times as the drum is required to rotate in said direction, for the purpose set forth.

5. The combination in a telephone apparatus, of a fixed bell-box, a casing fixed with respect to the bell-box and having a partition whereby it is divided into chambers, a drum arranged in the chamber of the casing remote from the bell-box, a spring also located

in said chamber and arranged to be put under tension by rotation of the drum in one direction and to rotate the drum, when released, in the opposite direction, and wires leading from the bell-box through the chamber of the casing adjacent to the bell-box and to the center of the drum and from thence to the periphery of the drum; the portions of the wires intermediate the bell-box and the drum being twisted in the direction opposite to that in which the drum rotates to pay off the wires one-half as many times as the drum is required to rotate in said direction, for the purpose set forth.

In testimony whereof I have hereunto set my hand in presence of two subscribing witnesses.

JAMES HARRY THOMPSON.
